UNITED STATES PATENT OFFICE.

MAJOR MILLER, OF LOWELL, WISCONSIN.

ADJUSTABLE BOOK-REST OR TABLE.

SPECIFICATION forming part of Letters Patent No. 653,107, dated July 3, 1900.

Application filed December 22, 1899. Serial No. 741,300. (No model.)

To all whom it may concern:

Be it known that I, MAJOR MILLER, a citizen of the United States, and a resident of Lowell, in the county of Dodge and State of Wisconsin, have invented a new and Improved Adjustable Book-Rest or Table, of which the following is a full, clear, and exact description.

One object of this invention is to provide a stand upon which a jointed arm is mounted for horizontal movement and upon which arm a table is carried for adjustment independent of the adjustment of the sections of the arm or the arm in its entirety, said table having such formation that it may be used as a rest or support for a book, for manuscripts, for sheets of music, or for letter-sheets or the like.

A further object of the invention is to provide means for vertically adjusting the supporting-arm and table carried thereby and also to provide a foot-rest which may be placed in different positions on the stand.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a perspective view of the improved device, the book-rest or table being in section. Fig. 2 is a side elevation of the upper portion of the device, showing the arm which carries the book-rest or table as projected forward to its full extent; and Fig. 3 is a longitudinal section taken substantially on the line 3-3 of Fig. 2 and looking in direction of the arrows in said figure.

The body of the device consists of a base A, provided with legs 10 of such character that the body of the device may be effectually sustained upon a floor or other suitable support, and the said body A is provided with an upright post 11, which is fast to the body and may be of any desired height. A sleeve B, which may be of any desired shape, is loosely mounted on the upright 11 and is free to turn thereon. This sleeve B is provided with a suitable opening at its center, which receives the upright 11, as shown in Fig. 3, and at the sides of the upright forwardly and

rearwardly extending openings 12 and 13 are produced in the said sleeve, as is also shown in Fig. 3, the said openings being adapted as 55 slideways for a supporting-arm C, to be hereinafter described. Thus it will be observed that the openings 12 and 13 form a central vertical tongue 12^a in the said sleeve.

The sleeve is held in adjusted position on 60 the upright 11 by means of an upper stop-collar 14, having a suitable set-screw 15, and a lower stop-collar 16, also provided with a set-screw 17. In the drawings, however, the lower stop-collar is shown out of engagement 65 with the sleeve B, since a foot-rest 18, loosely mounted on the upright 11, intervenes the bottom of the sleeve and the upper portion of the lower stop-collar 16, and this foot-rest is provided with curved recesses 19 in its upper 70 face at each side of its center, which recessed portions of the foot-rest are adapted to receive the ankles of a person using the device, the calf of the leg, or any other portion of the limbs which may need to be supported. Although I have shown this foot-rest as located 75 immediately below the sleeve B, it will be understood that said foot-rest 18 may be placed below the lower stop-collar 16 and have bearing against the base A, if so desired. 80

The supporting-arm C above referred to is made in pivotally-connected sections. In the drawings the arm is illustrated as comprising three sections—a rear section 20, an intermediate section 21, and a forward section 22. 85 The rear section 20 is provided with a central opening 20^a, receiving the web of the sleeve B, and the sides of this section are adapted to slide in the ways or openings 12 and 13 in the said sleeve B, as illustrated in Fig. 3. 90 The opening 20^a of the rear end section 20 of the arm C does not extend to the rear end of said section, and its sides at the forward end of the section are recessed to receive cheeks 20^b, preferably of metal, and these 95 cheeks are connected by pivot-pins 23 with the central section 21 of the said supporting-arm. This central section 21 comprises two side portions 21^a, made in either one or two pieces, and recesses 21^c are made in the forward and rear ends of this intermediate section, the rear recesses 21^c receiving the forward ends of cheeks 21^b of the rear section of said arm. The forward section 22 is of 100

similar construction to the rear section 20, and said forward section 22 of the arm is provided with a slot 22^a at its rear end and recesses in the outer side portions of the said 5 rear end, in which recessed portions cheeks 22^b are secured, and these cheeks, at their rear ends, enter the forward recesses 21^c in the intermediate section, while pivot-pins 24 are passed through the forward recessed portions 10 of the intermediate section 21 of the arm C and through the cheeks 22^b of the forward section of said arm, as is clearly shown in Fig. 3. Thus it will be observed that the arm has end movement through the sleeve B to a limited extent, the extent of end movement of the arm being such that the intermediate and forward sections 21 and 22 may be adjusted in an upward direction in front of the body portion of the device or whereby 15 the central section may be brought within the sleeve B and the end sections of the arm C folded upward at each side of the sleeve, so as to occupy but little room when the device is not in use.

20 25 A table or a book-rest D, usually provided with a bottom flange d, is carried by the arm C at its forward end. The connection between the table or book-rest and the arm C is effected by forming ears 25 at the back of the table or book-rest, which receive between them the forward end of the forward section 22 of the said supporting-arm C, and a screw provided with a thumb-nut 26 is passed through the said ears 25 and through the said 30 35 arm C, which enables the book-rest or table to have adjustment on the arm, enabling the table to be placed in a vertical position, as shown in Fig. 2, in an inclined position, as illustrated in Fig. 1, or in a horizontal position above the arm, if so desired.

40 45 It is evident that through the medium of the jointed arm C the table or book-rest may be given any desired inclination and that the height of the table or book-rest may be regulated by the vertical adjustment of the car-

rying-sleeve B. It is also obvious that the table or book-rest and arm may be conveniently carried out of the way by swinging the arm C from one side to the other. Thus it will be observed that this device provides a 50 table or book-rest which may be accommodated to a person occupying a chair, whether in a reclining or in an upright position, or may be adapted to the convenience of a person reclining upon any support.

55

Having thus described my invention, I claim as new and desire to secure by Letters Patent—

1. A book-rest or table, comprising a base, an upright on said base, a sleeve having a 60 transverse opening and mounted to move vertically on said upright and also to rotate thereon, an arm having a portion for passing through the opening in said sleeve, a swinging section for the arm, a table adjustable on 65 said swinging section, collars on the upright for holding the sleeve as adjusted, and a foot-rest movable vertically on and adapted to rotate on the upright, substantially as specified.

2. A book-rest or table, comprising a base, 70 an upright on said base, a sleeve mounted to move vertically on said upright and also to rotate thereon, the said sleeve having two openings extended horizontally through it, an arm having side portions for passing respectively through said openings, a vertically-swinging section for the arm, a table adjustable on said swinging section, collars on the upright for holding the sleeve as adjusted, and a foot-rest movable vertically on 75 80 and adapted to rotate on the upright, substantially as specified.

In testimony whereof I have signed my name to this specification in the presence of two subscribing witnesses.

MAJOR MILLER.
